US00D867148S

(12) **United States Design Patent** (10) Patent No.: **US D867,148 S**
Castillo Higareda et al. (45) Date of Patent: **** Nov. 19, 2019**

(54) **BOTTLE**(71) Applicant: **S. C. Johnson & Son, Inc.**, Racine, WI (US)(72) Inventors: **Jose de Jesus Castillo Higareda**, Racine, WI (US); **Peter M. Neumann**, Racine, WI (US); **Holger Hampf**, Munich (DE); **Matthew D. Hern**, Malibu, CA (US); **Gary B. Swetish**, Racine, WI (US); **Benjamin R. Lloyd**, Milwaukee, WI (US)(73) Assignee: **S. C. Johnson & Son, Inc.**, Racine, WI (US)(**) Term: **15 Years**(21) Appl. No.: **29/685,317**(22) Filed: **Mar. 27, 2019****Related U.S. Application Data**

(60) Division of application No. 29/640,135, filed on Mar. 12, 2018, now Pat. No. Des. 849,544, which is a division of application No. 29/512,929, filed on Dec. 23, 2014, now Pat. No. Des. 814,932, which is a division of application No. 29/412,300, filed on Feb. 1, 2012, now Pat. No. Des. 722,882, which is a continuation-in-part of application No. 29/380,459, filed on Dec. 6, 2010, now Pat. No. Des. 660,714.

CLAIM

The ornamental design for a bottle, as shown and described.

DESCRIPTION

FIG. 1 is a perspective view of a bottle showing our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines in the drawings illustrate the portions of the bottle that form no part of the claimed design.
